HAIR CURLING APPARATUS

William B. Tubbs, Chicago, Ill., assignor to
Hollywood Cone Waving Company, Saginaw,
Mich., a corporation of Michigan

Application August 9, 1933, Serial No. 684,343

7 Claims. (Cl. 132—33)

This invention relates to hair curling apparatus and is particularly directed to a hair waving rod for permanent hair waving.

An object of this invention is to provide a device of the character described having improved means for tensioning the hair wound on the rod and for retaining the hair in tensioned condition.

A further object of this invention is to provide a neat, compact and rugged curling device of the character described which shall be comparatively inexpensive to manufacture, comprise few and simple parts, be easy to assemble and manipulate, and which shall nevertheless be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, the scope of application of which will be indicated in the following claims.

In the accompanying drawing, in which is shown one of the various possible illustrative embodiments of this invention,

Fig. 1 is a perspective view of a head with a lock of hair wound on my improved curler, and illustrating my improved method of preparing the hair for permanent waving;

Fig. 2 is an elevational view of a hair curler embodying the invention;

Fig. 3 is an enlarged view of the curler structure shown in Fig. 2, with parts broken away to show the interior construction;

Fig. 4 is a cross-sectional view taken on line 4—4 of Fig. 3;

Fig. 5 is a view similar to Fig. 2, but illustrating a modified construction; and

Fig. 6 is an enlarged view of the structure shown in Fig. 5 with parts broken away to show the interior construction.

Referring now in detail to the drawing, 10 designates a head having a lock of hair 11 wound on a curling device 12 embodying the invention.

The device 12 comprises an elongated tubular member 13 having an axial bore 14 and formed with a plurality of adjacent pairs of oppositely disposed truncated conical surfaces 16 and 17. The pairs of truncated portions are disposed base to base thus forming a succession of grooves and are preferably of gradually decreasing diameter longitudinally from one end of the member 13 to the other, whereby said member is of generally tapered form. At the thicker end thereof, said member 13 is formed with a cylindrical portion

18, provided adjacent the outer end thereof with an annular groove 19. Slidably and rotatably extending within the axial opening 14 is a rod 22 formed with screw threaded portions 23 and 24 at the opposite ends thereof, projecting from the opposite ends of said member 13. Screwed to the threaded portion 24 is a member 25 having a threaded opening 26 for receiving said threaded portion 24. The member 25 is furthermore formed with an annular groove 26a of semi-circular transverse cross-section in an intermediate portion thereof. The outer end of said member 25 is formed with a transverse through slot 27 for the purpose hereinafter appearing. Preferably, the member 25 is fixed to the threaded end 15 of the rod whereby said rod may be rotated by turning said member. The end rod 22 may be fixed to member 25 in any other suitable manner. Disposed within the groove 19 and fixed to the member 13 is a small curved strip of spring metal 20, or pawl 30 having the inner end thereof 31 soldered or otherwise suitably fixed at the bottom of said groove. The member 30 curves spirally so that the outer end thereof normally projects slightly beyond the groove. The outer end of the spring 30 is preferably formed with a notch 32 forming two spaced points 33 for the purpose hereinafter appearing.

Slidably and rotatably received on the cylindrical portion 18 is a member 40 having a central bore or socket 41 for receiving said cylindrical portion. The outer surface of said member 40 may be of octagonal shape so as to facilitate finger manipulation for rotating the same. The end wall 43 of said member 40 is provided with an axial screw threaded opening 44 to which may be screwed the screw threaded portion 23 of the rod 22. Preferably interposed between the end wall 43 of the member 40 and the adjacent end of the member 13, is a spring washer 45 and a flat washer 46.

As shown in Fig. 3 of the drawing, the member 40 covers the groove 19. The outer end of the spring 30 engages the inner surface of said member 40, thus permitting turning of said member 40 in one direction relative to the tubular member 13 and preventing rotation of the member 40 relative to the member 13 in the opposite direction. The member 40 is thus clutched to the tubular member 13. In assembling the device, the end of spring 30 is pushed into the groove to permit member 40 to be fitted into the cylindrical portion 18.

The manner of using the device will now be described. A lock of hair is wound on the curling

device from the end 25 which is placed adjacent to the scalp toward the outer end, the rod being held substantially normal to the surface of the head. The lock of hair is wound tightly about the truncated portions helically outwardly. The inner end of the lock is tied to the member 25 by a string or the like, which may be passed through the slot 27 and in the groove 26 for firmly attaching the lock of hair to said member 25. The outer end of the lock of hair is tied to the cylindrical portion 18. Thereafter, the device 12 is held at the cylindrical portion 18 in one hand and the member 40 rotated relatively to the member 13, with the other hand. Rotation of the member 40 causes rotation of the member 25, to which the inner end of the lock of hair is tied firmly. Since the outer end of the lock is tied to the member 13 rotation of the member 25 will cause the hair to become more tightly wound and tensioned on the curler. Of course, the lock of hair must be wound in a direction opposite the direction in which member 40 may be rotated, so that rotation of said member will serve to tension the wound lock. By making the truncated portions 16 and 17 reduce gradually in diameter so that the member 13 is generally substantially tapered from the outer end to the inner end, the lock of hair after it is wound on the curler produces a substantially cylindrical outer surface, the hair being thicker near the scalp and thinner toward the ends thereof. Further with this construction substantially uniform, waves are obtained as the lock of hair is thicker at the scalp and gradually thins outwardly. After the hair is wound on the curling device, and hair waving pad wrapped therearound, the usual cylindrical electrical heater may be readily applied thereon.

The direction of the threads 23 is preferably such that rotation of member 40 will tend to screw said member further on the rod 22 to prevent looseness of the parts when a lock of hair is being tensioned.

In Figs. 5 and 6 is shown a modified construction similar to the device shown in Figs. 1, 2, 3 and 4, excepting that the truncated portions 16a and 17a, increase gradually in diameter toward the scalp end 25 of the device. This curler which tapers generally toward the scalp end thereof is for use preferably with hair longer than six inches and develops a larger wave at the scalp decreasing gradually toward the outer end where are formed smaller curls.

It will thus be seen that there is provided a device in which the several objects of this invention are achieved, and which is well adapted to meet the conditions of practical use.

As various possible embodiments of this invention might be made, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A curling device comprising an elongated member having adjacent pairs of oppositely dis-

posed truncated conical surfaces of longitudinally decreasing diameter.

2. A curling device comprising an elongated tubular member, a rod extending through said tubular member and projecting from the ends thereof, members attached to the projecting ends of said rod and means for clutching one of said last mentioned members to said tubular member, the outer surface of said tubular member having adjacent pairs of oppositely disposed truncated conical portions. 5

3. A curling device comprising an elongated tubular member, a rod extending through said tubular member and projecting from the ends thereof, a pair of members attached to the projecting ends of said rod and means for clutching one of said last mentioned members to said tubular member, the other of said pair of members being formed with a transverse slot, said tubular member being formed with oppositely disposed 15 conical surfaces.

4. A curling device comprising a tubular member having a generally tapering portion and a cylindrical portion at one end extending from the tapering portion, a member received on one 25 end of said tubular member and having a socket rotatably receiving said cylindrical portion, said cylindrical portion having an annular groove, a pawl attached to the bottom of the groove and engaging said socketed member, a rod extending through said tubular member and attached at one end to said socketed member, and a member attached to the opposite end of said rod. 30

5. A curling device comprising an elongated tubular member having a plurality of adjacent 35 pairs of oppositely disposed truncated conical surfaces of gradually decreasing diameters longitudinally, said tubular member having a cylindrical portion at one end thereof, a rod extending through said tubular member and beyond the 40 ends thereof, a member fixed to one end of said rod, and a member screwed to the opposite end of said rod and rotatably receiving said cylindrical portion, said cylindrical portion being formed with an annular groove, and a spring 45 within said groove fixed at one end thereof to the bottom of said groove and the opposite end of said spring contacting said last member.

6. A curling device comprising an elongated tubular member having pairs of oppositely disposed truncated conical surfaces of longitudinally decreasing diameter, said member having an axial opening, a rod extending through said opening and extending beyond the ends thereof, members attached to the projecting ends of said rod, 55 and means for permitting rotation of one of said last mentioned members with respect to said tubular member, in one direction and preventing rotation of said member with respect to said tubular member in the opposite direction. 60

7. A device for use in permanent hair waving apparatus including a rod of generally tapering form and having shallow surface grooves in succession from near the scalp end, the grooves being formed between portions of truncated 65 cone-like forms set base-to-base.

WILLIAM B. TUBBS.
